UNITED STATES PATENT OFFICE.

GRACE G. DRAYTON, OF NEW YORK, N. Y.

DESIGN FOR A FIGURE TOY.

52,022.

Specification for Design.

Patented May 7, 1918.

Application filed February 2, 1918. Serial No. 215,204. Term of patent 3½ years.

To all whom it may concern:

Be it known that I, GRACE G. DRAYTON, a citizen of the United States, residing at New York, in the county of New York and State of New York, have invented a new, original, and ornamental Design for a Figure Toy, of which the following is a specification, reference being had to the accompanying drawing, forming a part thereof.

Figure 1 is an elevation of a figure toy, illustrating my new design, and

Fig. 2 is a plan view.

I claim:

The ornamental design for a figure toy, as shown.

GRACE G. DRAYTON.
